ATTORNEY

UNITED STATES PATENT OFFICE

ERNEST O. HOWLE, OF CHICAGO, ILLINOIS, ASSIGNOR, BY MESNE ASSIGNMENTS, TO
MID-WEST INCINERATOR CORPORATION, OF CHICAGO, ILLINOIS, A CORPORATION OF
DELAWARE

CHIMNEY CONSTRUCTION

Application filed November 18, 1927. Serial No. 234,222.

My invention relates to improvements in chimney constructions, more particularly those used in connection with incinerators, refuse burners, etc., and it consists in the combinations, constructions, and arrangements herein described and claimed.

An object of my invention is to provide means whereby sparks such as those produced by burning paper or rags will be prevented from escaping from the stack or flue while being burned.

A further object is to provide a simple and effective means for arresting particles such as paper and rags before the particles can enter a screen trap at the upper end of the flue, and permitting the particles to be consumed, thereby eliminating the danger of the particles stopping up the screen.

A further object is to provide a device which is efficient in blocking flying particles and at the same time reducing to a minimum the danger of slowing down the draft.

Other objects and advantages will appear in the following specification, and the novel features of the invention will be particularly pointed out in the appended claims.

My invention is illustrated in the accompanying drawings, forming part of this application, in which

Figure 1 is a vertical section through a portion of an incinerator with my invention applied thereto.

Figure 2 is a horizontal plan view along the line 2—2 of Figure 1 with the screen removed,

Figure 3 is a modified form of baffle, and

Figure 4 is another modified form of baffle.

In Figure 1, I have shown a portion of an incinerator to which my invention has been applied. This consists of a shaft 1 having filling openings such as those shown at 2 and 3. These openings may be on various floors, as where the incinerator forms part of the equipment of an apartment building, and may be provided with doors 4. The shaft 1 extends to a furnace 5 of any suitable type. The shaft has preferably a partition 6 to provide a smoke flue 7 and a refuse chute 8 leading to the chimney 9.

Near the top of the latter is a metal frame

10 which is disposed on the interior and which has rods 11 running across the chimney as shown in Figure 2. On these rods are supported baffle plates 12 and 13, whose ends are bent to retain them in position. Referring to Figure 2, it will be seen that the plates 12 and 13 are perforated and that the openings 12' and 13' are relatively close together. In the drawings, I have shown only two of these plates, but more might be used without departing from the spirit of the invention. It will be observed that the plate 13 covers substantially one half of the area of the chimney, while the plate 12 covers the other half, and that between these two plates is a space, whereby the products of combustion may pass upwardly. The said plates incline upwardly toward opposite sides of the flue to provide pockets in which burning paper carried upwardly by the draft will be trapped. The perforations in the plates 12 and 13 permit the draft to pass through the plates and thereby insures that the burning particles of paper will be carried into the said pockets. Surmounting the chimney is a screen 14, preferably of wire mesh.

From the foregoing description of the various parts of the device, the operation thereof may be readily understood. The refuse, which it is desired to burn, may be deposited in the chute 8 by opening one of the doors 4, such as the upper door shown in Figure 1. This refuse may consist partly of light material, such as paper, which may pass downwardly into the furnace, take fire, and then be carried upwardly by the draft. It is a tendency for paper, that is, loose paper, when it once enters the flue to spread out and be carried upwardly by the draft. Thus it will be seen that ordinarily these flying particles of paper would pass through the chimney or flue and into the screen, thereby eventually blocking the screen. I have found that with the perforated baffles as arranged, articles such as newspapers and similar light material will be trapped by the baffles and held there while being consumed. The purpose of the perforated baffles is of course to provide a direct draft that is to say, there is no slowing down of the draft, and pieces of newspaper,

etc., will not be caused to be deflected from the baffles or pass through the space between the two baffles.

When the draft due to the burning material has lessened, then the matter held by the baffles will fall down the chute into the furnace and there be consumed. Should the baffle plates at any time becomes accidentally covered or blocked with loose paper and the like, the space between the two plates will of course permit the products of combustion to pass upwardly, thereby preventing the possibility of the chimney becoming entirely blocked.

I have found that with this arrangement the clogging of the screen 14 by matter which would otherwise pass upwardly is eliminated without, however, causing the smoke to enter the living quarters through the openings such as those shown at 2 and 3, the reason being that, while the matter which would tend to clog the screen is trapped underneath the baffles, the smoke and products of combustion can pass on outwardly through the openings in the baffles and the space between the baffles and then, as stated, said matter will fall down into the furnace when the draft has decreased.

The inclination of the baffles and the distance between them of course are matters which depend upon the dimensions of the chimney or chute. Such changes, however, would fall within the spirit and the scope of the invention.

In Figure 3, I have shown a plan view of a modified form of baffle. This baffle consists of screen sheets 20-20 made from any suitable wire fabric, the sheets 20-20 being overlapped in the manner shown in Figs. 1 and 2. Figure 4 shows a further modification of the baffle. This baffle consists of overlapping plates 21-21.

I claim:

1. The combination with a chimney, of a frame disposed on the interior thereof near the top, transverse rods carried by said frame, a baffle plate having air passages therethrough carried by certain of said rods, said plate extending downwardly and inwardly from one wall of the chimney to substantially the center thereof to provide a pocket trap through which the draft will pass, and a second baffle plate mounted on others of said rods and extending downwardly and inwardly from the opposite wall, the inner ends of said baffle plates being spaced apart to provide a passage for the products of combustion.

2. The combination with a chimney, of a frame extending into the chimney from the upper end thereof, transverse rods carried by said frame, a baffle plate carried by certain of said rods and having openings therein for the passage of air, said plate extending downwardly and inwardly from one wall of the

chimney to substantially the center thereof to provide a pocket trap converging toward its upper end, a second baffle plate mounted on others of said rods and extending downwardly and inwardly from the opposite wall, the inner ends of said baffle plates being spaced apart to provide a passage for the products of combustion, and a screen surrounding the chimney.

Signed at Chicago, in the county of Cook and State of Illinois, this 11th day of November, A. D. 1927.

ERNEST O. HOWLE.
